B. SAAD

CHECK PROTECTOR

Filed June 27 1923

Inventor

Bedri Saad.

Attorneys

James Shatley & Co.

UNITED STATES PATENT OFFICE.

BEDRI SAAD, OF YAKIMA, WASHINGTON.

CHECK PROTECTOR.

Application filed June 27, 1923. Serial No. 648,129.

To all whom it may concern:

Be it known that I, BEDRI SAAD, a citizen of Syria, residing at Yakima, in the county of Yakima and State of Washington, have 5 invented new and useful Improvements in Check Protectors, of which the following is a specification.

My present invention pertains to devices for making checks and it contemplates the 10 provision of means whereby through the use of this check making device the numbers will not only be readily produced on a check but the maker of such check will be protected to the extent that once the 15 numbers have been produced the liability of erasing the numbers is effectually precluded.

The invention further contemplates the provision of a portable check protector that 20 will be readily and easily fastened to a check-book and carried about on the person.

Further objects and advantageous characteristics of the invention will be fully understood from the following description and 25 claims when the same are read in connection with the drawings accompanying and forming part of this application in which:—

Figure 1 is a top plan view of a portion 30 of the device with one of the plates removed therefrom.

Figure 2 is a perspective view illustrating the complete check making device.

Figure 3 is a perspective view showing 35 the device entirely open.

Figure 4 is a longitudinal sectional view taken through the device and ready for operation.

Similar numeral of reference designate 40 corresponding parts in all the views of the drawings.

My novel check printing device comprises two sections, the upper one of which is indicated by 1 and the lower one of which is indicated by 2 and on one side of the section 45 1 I provide a stud 3 and on the lower section 2 and at the corresponding side to which the stud 3 is secured I arrange a lateral hook 4 whereby when the two casings 50 are brought together they will be held in said position by means of the hook and stud.

Arranged on a pintle 7 that passes through the ears 6 is a bar 5 that is formed integral with the ears and the said pintle 7 55 extends entirely through and secures the

sections 1 and 2 in hinged manner with respect to each other.

Arranged on and revoluble within the casing 1 is a knob 8 that is fixedly secured to the disk 9 that is provided with the peripheral notches 10 but successively engage a spring 11 whereby upon turning of the disk to indicate one of the numerals the disk will be temporarily locked so as to prevent slipping of the disk during a 60 printing operation.

On its inner side the casing is provided with an opening 11^a through which the numerals 12 appear. These numerals are the ones that cut or indicate the amount to be 65 produced on a check and are preferably serrated as indicated by 12^a.

On its upper side the casing 1 is provided with the sight opening 13 through which the small numerals 14 appear. It 70 will be manifest that the disk is provided on one face with eight numerals 14 and on its opposite face with printing numerals 12 and it will also be apparent that these openings are out of registration with each other. 75

At its end adjacent the pintle 6 the casing 1 is provided with an ink pad 15 and although I have shown the pad as a flat element I would have it distinctly understood that this pad may be eliminated and 80 a roller substituted therefor; the purpose being to provide an inking surface that will engage or ink the serrated surfaces 12^a of the numerals 12 during rotation of the disk 9.

Arranged so as to engage the numerals 12 when the casings 1 and 2 are brought to bear upon each other and positioned in the inner surface of the casing 2 is a metal portion or platen 16 having V-shaped grooves 95 and at its end the casing 2 is provided adjacent the portion 16 with a slot 17 having notches 18 that engage the ledge 19 of a lever 20 that is fulcrumed at 21 by means of a pin.

Secured to the inner end of the lever 20 is a sliding check feeding element 22 and said sliding element is secured to the lever 20 by means of a pin 23. A slot 24 is formed in the under surface of the casing 2 immediately below the pin 23 and this slot is indicated by 24. This provision is made in order that the sliding member will travel evenly in the opening 25 in which the sliding member operates. On its upper surface 100 105 110

the sliding member is provided with the prongs 26 that engage the check C.

A plate 27 that is hinged on the pintle 7 bears against the upper surface of the 5 check and springs 28 are adapted to depress the plate 27 so as to force the check firmly against the prongs but at the same time the tension of these springs is such so as not to impede operation of the sliding 10 member. A ledge 29 is formed on the casing 1 and this ledge coacts with the lip 30 of casing 2.

On its edges the plate or casing 2 is provided with serrations to hold the check from 15 shifting during operation of the device.

In the practical use of the invention, the check is placed in the device as indicated in Figure 4 with the plate 27 bearing on the upper surface of the check and the 20 prongs 26 bearing on the under surface of the check. The operator then turns the knob 8 to the desired numeral and merely presses downward or in other words brings the two casings 1 and 2 together. This immediately 25 brings the numeral appearing at the sight-opening so that it will bear upon the check surface at the point immediately above the portion or female die 16 of the casing 2. The casing 1 is then lifted slightly above 30 so as not to bear on the check and the lever 20 is moved one notch which in turn moves the sliding element 22 that imparts movement in one direction to the check. The operator then turns the knob to the desired 35 numeral and repeats the printing operation above indicated. Any number of printing operations may be accomplished and this without moving the check in any other manner than through the lever 20.

40 The device is so constructed and arranged that it may readily be locked and carried with ease in the pocket of a person and is instantly ready for use and because of its compact construction it will manifestly take 45 up but a very small amount of space.

Having described my invention, what I claim and desire to secure by Letters-Patent is:—

1. In a check printing device the combination of two hinged casings, a sight opening 50 formed in one of the casings on its upper surface and an opening formed in the said casing on its under surface; each of said openings being out of registration, a disk 55 arranged in the casing and having numerals on both of its surfaces, peripheral notches formed in the disk, a spring having a tooth that engages the notches, a pintle extending across the inner end of the first casing, lips 60 formed on the pintle, an inking element arranged in the casing, a plate mounted on the second casing, a bar fulcrumed in the second casing and a slidable member arranged to travel in a channel formed in the 65 second casing and having prongs on its up-

per surface and secured to the last named bar, a ledge secured to the bar and notches for engaging the ledge formed in one end of the second casing and a platen secured on the inner face of the bottom casing; said casings being hinged one to the other. 70

2. In a check printing device the combination of an upper casing, a disk revoluble in the casing and having numerals thereon, an inking pad arranged to bear on the numerals, a second casing secured to the first casing, a plate secured to the hinging element of the casings, springs adapted to bear on the plate, a lever having a slidable check feeding member arranged on one end thereof, and a platen mounted on the second casing and adapted to receive and bear against the numerals. 75

3. In a check protector, the combination of two hinged casings; one of said casings 80 having a sight opening on one surface and a printing opening on the opposite surface, a disk movable in the casing and having numerals arranged on both of its surfaces and adapted to travel over an inking surface, a lever formed in the second casing and movable independently thereof and having a slidable member operatable by the lever and adapted to engage a check, and means for lightly bearing on one surface 85 of the check to prevent shifting in endwise manner of the check during movement of the slidable member. 90

4. In a check writing and protecting device the combination of a casing, a sight 100 opening formed in one surface and a printing opening formed in the opposite surface, a disk revoluble in the casing, numerals formed on the disk, notches formed on the disk, means for temporarily locking the disk with respect to the casing, means in the casing for inking the numerals, springs formed in the casing adjacent the inking element, a pintle extending across one end of the casing, a stud formed on the casing, 105 a second casing hinged to the first casing by said pintle, a lever fulcrumed in the second casing and having a ledge that engages notches of the second casing, a check sliding device secured to the lever, a plate bearing on the check sliding device, a lip formed on the inner end of the second casing and a ledge formed on the inner end of the first casing; said lip and notch engaging each other, and a hook adapted to 110 engage the stud of the first casing to hold the casings closed. 115

In testimony whereof I have hereunto set my hand in presence of two subscribing witnesses.

BEDRI SAAD.
